UNITED STATES PATENT OFFICE.

RAYMOND P. SLOAN, OF MEDIA, PENNSYLVANIA

PRINTING-MACHINE

1,228,074.

Specification of Letters Patent. Patented May 29, 1917.

Application filed July 15, 1916. Serial No. 109,441.

To all whom it may concern:

Be it known that I, RAYMOND P. SLOAN, a citizen of the United States, residing in Media, in the county of Delaware and State 5 of Pennsylvania, have invented certain new and useful Improvements in Printing-Machines, of which the following is a specification.

This invention relates particularly to 10 printing machines of the class known as check writers or check protectors in which the mechanism is so constructed as to print or apply upon the check or other instrument or paper characters of various kinds, 15 such as numbers, words and letters, to indicate the amount or approximately the amount for which the check or other instrument was originally drawn or written and in such manner that the characters thus 20 printed or applied cannot be changed without detection.

In such machines a wheel, disk or the like 25 is provided with the necessary number of words and characters, and mechanism is provided for bringing any one of the several words and characters or sets thereof into printing position. Means is also provided for inking the characters and a platen cooperates with the printing wheel to make 30 impressions on the paper when the proper character or word has been selected.

It is often necessary to print a series or 35 succession of characters on the paper and therefore such mechanism is provided with devices for feeding the paper step by step after each word has been printed. As some words or characters are longer than others the feed mechanism is such that the paper is fed variable amounts corresponding with 40 the length of the word or character last printed and allowance is also made for providing a proper space between each succeeding character or sets of characters.

The object of my invention is to simplify 45 the construction of mechanism of the class above mentioned and to render the operation thereof more easy and reliable.

According to my invention the words, 50 numerals and other characters are arranged on a disk mounted to turn in a horizontal plane and operated by a hand-lever which moves the disk to any desired extent about its axis to bring the necessary word or character into printing position. Said lever,

while mounted to move in a horizontal plane 55 to turn the disk, is also pivoted to move vertically and to operate mechanism which actuates a platen that presses the paper against the selected characters, said lever also actuates devices of novel construction which 60 feed the paper to the required extent after each printing operation. During the actuation of said operating lever devices are operated which apply ink to the printing wheel while the paper is being printed. 65

Instead of forming projections within the outlines of the letters or characters on the printing wheel, such letters or characters are sunken or arranged below the surface of the disk, while projections are provided 70 which surround the outlines of the characters whereby when the printing is performed the letters or characters will be unbroken but will be surrounded by paper which is embossed, mutilated or scored and 75 which is also inked.

The mechanism is so constructed that all the operations may be performed by the manipulation of a single handle which turns the printing wheel or disk to printing position, actuates the platen to effect the printing, causes ink to be applied and thereafter automatically releases the platen and the inking device and operates the feed mechanism to advance the paper the proper extent no matter what may be the length of the word or character last printed. 80

The mechanism for actuating the feed of the paper is simple but reliable, comprising a plate which has a variable movement corresponding with the length of the character last printed and which imparts a variable movement to the mechanism which operates the paper-feed rolls. 90

Other features of my invention will be 95 hereinafter specified.

In the accompanying drawings,

Figure 1 is a perspective view of a printing machine embodying my improvements.

Fig. 2 is a plan view of a check showing 100 how characters are printed thereon.

Fig. 3 is an enlarged view of a portion of the check showing the kind of characters employed and the way in which they are surrounded by mutilated portions of paper. 105

Fig. 4 is a detail view and in section on the line 4-4 of Fig. 3 but on an enlarged scale.

Fig. 5 is a top plan view of the machine.

Fig. 6 shows a longitudinal central section on the line 6—6 of Fig. 5.

Fig. 7 shows a horizontal section on the 5 irregular line 7—7 of Fig. 6.

Fig. 8 shows a transverse section on the line 8—8 of Fig. 6.

Fig. 9 is a detail view in perspective showing particularly parts of the paper feed 10 mechanism.

Fig. 10 is a perspective view of a portion of the inking devices.

Fig. 11 is a perspective view of the annular ink pad preferably employed.

15 Fig. 12 is a detail view in section showing the relation of the paper feed rolls with the co-operating pressure rolls.

Fig. 13 is a plan view of the gage wheel.

20 Fig. 14 is a bottom plan view of the printing wheel.

Fig. 15 is a view on a greatly enlarged scale showing portions of the printing wheel.

25 Fig. 16 is a detail view in section on the line 16—16 of Fig. 15.

Fig. 17 is a detail view in section on the line 17—17 of Fig. 15.

30 The base A of the machine is provided with a bottom piece a carrying soft feet a' and from the base rises a frame B of suitable shape or construction to support some of the mechanism. A hood B' supported on the frame covers certain parts of the mechanism contained in the rear portion of 35 the machine.

40 The printing wheel C is arranged horizontally to turn about a vertical axis. It may be constructed or equipped to print letters, numbers, words or other characters either by indenting the paper, embossing it, mutilating it or in any other suitable way.

45 I preferably construct the wheel to produce the letters or other characters by both mutilating the paper and also applying ink thereto. The way in which this is done will be hereinafter described. The printing wheel is attached to the lower end of a sleeve c through which extends a shaft c' secured at its upper end to the machine frame at b. Near its upper end the sleeve c carries a pinion d meshing with a toothed segment D, the hollow hub d' of which is elongated and extends upwardly through 55 the frame B. The hub is slotted at d' and through this slot extends an operating lever E which is pivoted to move about the horizontal axis of the rod e which is carried by the bifurcated lever support e' 60 clamped at e' to the hub of the segment and resting on a rail e' formed on the top of the machine frame. The lever E extends forwardly from its support and carries a handle e' and it also carries a pin e' adapted to enter any one of a series of holes f

formed in the curved rail F at the front of the machine. The surface of this rail is in a horizontal plane and just below its front edge there is an index formed on the curved flange f'. The index may bear any desired 70 designation of numbers, words, characters, etc., but they should correspond with the numbers, words, characters, etc. on the printing wheel.

A pointer G is attached to the lever support e' and moves coincidently with the operating lever. It is arranged directly below this lever and it is formed with an opening g through which the pin e' of the lever is adapted to pass, the arrangement being such that when the lever is moved to such a position that the pointer designates a particular number or character it may be depressed and the pin e' will enter a hole f corresponding with the number or character 85 designated by the pointer.

The rear or inner end of the lever E is bifurcated and engages a pin h carried by a cylindrical rod H the upper end of which extends into the hub d' of the segment D 90 and is free to move up and down therein. Surrounding the rod H is a sleeve I which is held in place on the rod by a washer i secured to the rod by a screw i'. The upper end of the sleeve I bears against a shoulder j' formed on the upper end of the rod. By this construction the sleeve, while free to turn on the rod, is prevented from moving endwise thereon and it is raised and lowered when the rod is correspondingly 100 moved.

Arms I' extend horizontally forward from the sleeve I and serve to raise the frame J of the inking device K. Said frame J, as shown in Fig. 8, is supported by screws j' attached to the machine frame and carrying springs j' which tend to press the frame downward but which permit it to be raised at the proper time. I preferably employ an inking pad k (Fig. 11) which is carried by a pad frame k' supported by the frame J in such manner as to move up and down therewith. The pad frame and the pad are formed with openings k' to receive the platen as hereinafter explained. Access 110 may be had to the inking pad through an opening in the frame closed by a removable cover, Y.

The construction thus far described is such that by turning the lever E in a horizontal plane the printing wheel may be turned to different positions and by depressing the operating lever the printing wheel may be locked in its adjusted position and further when the outer end of the lever is 125 depressed its inner end is raised and by the engagement of the arms I' with the frame J, the inking pad is raised to apply ink to the printing wheel. As soon as the lever E is raised the arms I' are withdrawn from 130

the frame J and the springs j' return the inking device to its normal position away from the printing wheel.

5 A bifurcated lug l is formed on the rear side of the sleeve I and it carries a pin l' with which engages the bifurcated end of a lever L, pivoted at l² on a standard l³ rising from the frame base A. This lever extends rearward and upward from the standard l³ and is jointed at its upper rear end to a link M jointed at its lower end m² below the base plate to a horizontally arranged lever M' which is pivoted at m³ to a hanger m⁴ depending from the base plate.

10 Said lever carries at its front end the platen N. A pivotal connection is made at n between the platen and the lever and the arrangement is such that when the operating lever E is depressed the platen is raised by means of the mechanism just described. The platen is faced with some suitable soft material n', such as leather.

15 The lever L, as shown, is made in two parts and between these two parts it carries a flanged roller o with which engages the arms of a bifurcated lever O, the upper portion of which extends upward between the two parts of the lever L. Said lever O is pivoted at m to the standard m' and it is jointed at o' to a link o², the lower end of which is pivoted at o³ to a block P mounted to slide on the machine frame between stops p, p'. A spring p² connects the lower end of the lever O with the lower portion 20 of the link o² and tends to hold said lever in the position shown in Fig. 6. Said spring also serves to move the lever O upwardly and, through the connections before described, to raise the outer end of the operating lever E to the normal position shown 25 in Fig. 6.

30 A rod Q has a front portion which extends through a hole in the flange or stop p' and it is adapted to slide therein. Said rod extends freely through a hole in the block P and it carries a collar q between which and the block is interposed a spring q' which tends to push the front end of the rod forward away from the block. The rear portion q² of the rod Q is enlarged and there is a shoulder q³ against which the block at times rests. The arrangement is such that when the block is moved toward the printing wheel it moves the rod forward, the spring q' pressing against the collar q and effecting this movement. When the block is moved rearward it engages the shoulder q³ and thus effects the rearward movement 35 of the rod.

40 The rod Q co-operates with a gage wheel R which moves coincidently with the printing wheel. It is preferably formed integrally therewith and is preferably arranged on its upper side. Said gage wheel 45 carries a series of stops r arranged radially

about the axis of the printing wheel and the outer ends of which are disposed at different distances from said axis. These stops are designed to co-operate with the rod Q, the forward end of which is adapted to engage them and they serve to vary the forward movement of the rod to regulate the feed of the check or paper in the manner hereinafter explained.

45 The rear end of the rod Q carries a downwardly extending pin s which enters the slot s' of a plate S mounted to slide transversely of the machine in suitable supports. The slot s' is diagonally arranged and when the rod Q is moved longitudinally a transverse movement is given to the plate S.

50 A lever T is pivoted at t to a bracket t' depending from the plate S and it is pivotally connected at its outer end t² to a pawl-carrier U equipped with a spring-pressed pawl u which engages a ratchet wheel u' fast on a shaft U carrying paper feed rolls u². The shaft U' is supported in suitable brackets u³ and the rolls extend through openings in the machine frame as 55 indicated in Fig. 8. The rolls u² co-operate with pressure rolls u⁴ carried by a shaft u⁵ extending through brackets u⁶ and carrying a hand-wheel u⁷. The shaft u⁵ is pressed downward by springs u⁸ in the brackets 60 whereby a yielding pressure is imparted to the pressure rolls and this construction also permits the rolls u⁴ to be raised away from the feed rolls u² when a check or other paper is being inserted into the machine. Such 65 check or other instrument to be printed upon is inserted beneath the printing wheel and below the inking device, suitable openings being left in the sides of the frame for this purpose. In order to gage the printing line 70 on the paper I may employ an adjustable gage V of any suitable kind. Preferably such gage comprises a plate v carried by a block v' adjustable in a slot v² in the frame and operated by a knob v³.

75 Before describing the operation of the mechanism I will refer more particularly to the construction of the printing wheel. As before stated, so far as much of my invention is concerned any device for making 80 marks or impressions on the paper may be employed, but preferably the machine is adapted to print letters, numbers, words and other characters. Some of those preferably employed are indicated on the index f', 85 Fig. 1.

85 It is quite usual in this class of machines to provide the printing wheel with raised type which are formed with ridges and grooves and such type co-operate with a 90 platen having corresponding ridges and grooves which register with those on the type, but I prefer to construct the printing wheel in the manner indicated in Figs. 14 to 17 of the drawings. As there shown the 95

wheel C is formed with sunken characters and words and the surface of the wheel surrounding these sunken characters is formed with projections which serve to puncture or mutilate the paper printed upon. As shown in Fig. 17 the grooves c^2 , which form the characters, are sunken in such manner that the ink does not reach their inner ends, while the surface of the wheel is formed with relatively short projections c^3 which receive ink and transfer it to the paper during the printing operation while at the same time puncturing or mutilating the paper.

It will be observed by reference to Fig. 6 that the projections c^3 are formed on raised portions of the wheel so that there is a blank space c^4 between each of said raised portions. In this way only a relatively small part of the paper is mutilated and printed around each word or character.

It will be observed by reference to Fig. 15 that the projections are formed by cuts α which are parallel with each other and by transverse curved concentric cuts α' . The cuts α in each set are parallel with each other but only the middle one of each group is truly radial. Suitable tools are employed to give to the projections sufficiently sharp points to properly cut or mutilate the paper and to transfer ink thereto.

Fig. 2 of the drawings shows a check of usual form and indicates how the word "ten" is printed thereon by my machine.

Fig. 3 shows on an enlarged scale how the letters appear on the check and how they are surrounded by mutilated portions of the paper.

In Fig. 4 y indicates that portion of the check carrying the characters, while y' indicates the parts which are mutilated and which are inked.

The check or other paper to be printed upon is placed in position below the printing wheel, while the different parts of the mechanism are in the position shown in Fig. 6. The pressure rolls may be raised while the paper is being inserted, or they may be turned by the hand-wheel u' to adjust the paper. This may also be brought into proper position by the gage V.

When the check or other paper is properly positioned and the word or character to be printed is determined upon the lever E is turned horizontally until the pointer G is directly over the character or word to be printed, for instance, "forty" (or 40) as indicated in Fig. 1. As the lever is thus turned the corresponding word or character on the printing wheel is moved to printing position directly over the platen and a stop r on the gage wheel R corresponding with the character or word to be printed is brought directly opposite the reciprocating rod Q, the machine is then ready to print. The operating lever is then depressed and the

platen N is raised and presses the paper against the printing wheel and the desired word or character is printed and at the same time the paper is indented or otherwise mutilated. During this downward movement of the operating lever the inking device is raised by means of the arms I and ink is applied to all of the raised portions of the printing wheel, except that portion directly over the platen which portion is at this time directly over the openings h' in the inking device. During said downward movement of the operating lever, the rod Q is moved forward until it strikes the stop r of the gage wheel directly in line with it and at the same time the plate S is moved in such manner as to cause the pawl u to move downwardly over the tooth of the ratchet wheel u' .

When the lever E is raised the rod Q is withdrawn from the gage wheel and the plate S is moved back to its normal position. In doing so, it causes the pawl u to turn the ratchet wheel and thus actuate the feed rolls.

It will be understood that it is often necessary to write more than one character or more than one word on the check or paper in succession and it is desirable that the check should be fed automatically after each impression. It is also obvious that inasmuch as the words, characters, etc. are of different lengths, the feed of the paper should vary

and that allowance should be made for a suitable space between the words and characters. My mechanism is so constructed as to accomplish these results. As before stated, the stops r on the gage wheel are set at varying distances from the center of the printing wheel and they serve to limit the forward movement of the rod Q so that said rod is moved to a different extent for different characters or words on the printing wheel. Inasmuch as the movement of the rod determines the movement of the plate S, it is clear that the feed rolls will be moved to an extent corresponding with the movement of the rod. In this way the paper is moved to a proper extent after each impression, the movement given to the paper being dependent upon the length of the character or word printed immediately preceding the operation of the paper feed mechanism.

When the rod Q is projected forward it strikes one of the stops r as before explained. If the word which this stop represents is a long one such as "seventeen," the spring q' is not compressed or is compressed to only a slight extent, but if the word is short, the movement of the rod will be arrested by the stop representing such short word and then the spring is compressed and no further movement is given to the rod. In this way the block P is allowed to move to the same

extent at each operation of the machine but the rod Q is moved variable extents. When the operating lever E is released or raised the block P moves rearward at first without moving the rod Q, but afterward the block strikes the shoulder q^3 and thereafter the rod is moved rearward and imparts a corresponding movement to the plate S and a like movement to the paper-feed mechanism. It will be understood that normally the pin s is at the rear end of the slot s', as indicated in Fig. 7. During the forward movement of the pin the pawl u rides over the teeth of the ratchet u' without moving the latter. The pin s is moved forward variable extents as before explained but when the operating lever E is released the pin s returns to its normal position and in so doing shifts the plate S and causes the pawl u to move the paper-feed devices.

The machine hereinbefore described is very simple in construction and is easily operated. After the check or other paper is once adjusted in the machine all operations may be performed by the actuation of a single operating lever and the mechanism is such that any desired word or character within wide limits may be printed or affixed to the paper and furthermore a succession of words or characters can be thus printed or affixed while the paper is being fed variable extents through the machine.

I claim as my invention:

1. A printing machine comprising a printing wheel having a flat face with a series of radially arranged characters, a platen for pressing the paper against the wheel, a lever for turning the wheel to printing position and for operating the platen, a flat inking pad, and means operated by the lever for moving the pad into contact with parts of the printing wheel and for coincidentally operating the platen to press the paper against another part of said wheel.

2. A printing machine, comprising a printing wheel mounted to rotate in a horizontal plane, a vertically moving platen co-operating therewith, a lever mounted to turn about a vertical axis to move the printing wheel to printing position and to turn about a horizontal axis for moving the platen toward the printing wheel, and an inking device operated by said lever to apply ink to the printing wheel during the upward movement of the platen.

3. A printing machine, comprising a printing wheel, a platen co-operating therewith, a lever for turning the printing wheel to printing position and for operating the platen, an inking pad, a pad carrying frame, and connections between the pad-carrying frame and the lever for moving the pad against the printing wheel during the operation of the platen.

4. A printing machine, comprising a hori-

zontally arranged printing wheel, a vertically moving platen co-operating therewith, a lever mounted to turn about a vertical axis to bring the printing wheel into printing position and to turn about a horizontal axis to move the platen toward the printing wheel, an inking pad, a pad-carrying frame, and connections between the pad-carrying frame and said operating lever for moving the inking pad into engagement with the printing wheel when the platen is actuated to perform the printing operation.

5. A printing machine, comprising a horizontally arranged printing wheel mounted to move about a vertical axis, a segment mounted to move about a vertical axis and geared with said printing wheel, a vertically moving rod extending through the segment, a platen co-operating with the printing wheel, connections between said vertically moving rod and the platen, and an operating lever connected with the segment to move it about its axis, which is pivoted to move about a horizontal axis, and is connected with said rod to move it vertically and thus actuate the platen.

6. A printing machine, comprising a printing wheel mounted to move about a vertical axis, a segment mounted to turn about a vertical axis and geared to said printing wheel, a vertically moving rod passing through said segment, a sleeve carried by said rod and movable vertically therewith but free to turn relatively thereto, a platen co-operating with the printing wheel, connections between said sleeve and the platen, and an operating lever connected with the segment for turning it about its axis, mounted to move about a horizontal axis and connected with the vertically moving rod to raise and lower it and thus actuate the platen.

7. A printing machine, comprising a horizontally arranged printing wheel mounted to turn about a vertical axis, a segment geared therewith and mounted to turn about an axis parallel with that of the printing wheel, a rod extending through the segment and movable vertically therein, a sleeve surrounding said rod, a platen, connections between said sleeve and the platen for operating the latter, a lever for operating the segment and rod, an inking device co-operating with the printing wheel, and arms extending from said sleeve for moving the inking device into engagement with the printing wheel.

8. A printing machine, comprising a printing wheel, a platen co-operating therewith, a lever for turning the printing wheel to printing position and for operating the platen, an inking pad having an opening through which the platen operates, a carrying frame for the pad, and connections between the pad-carrying frame and the lever.

for moving the pad against the printing wheel during the operation of the platen.

9. A printing machine, comprising a printing wheel mounted to turn about a vertical axis, a segment mounted to turn about a vertical axis and geared to said printing wheel, a vertically moving rod passing through said segment, a sleeve carried by said rod and movable vertically therewith 10 and free to turn relatively thereto, a platen cooperating with the printing wheel, a lever having one end connected with said sleeve and movable vertically therewith, a link connected to the opposite end of said lever, and 15 connections between said link and the platen for raising and lowering the latter.

10. A printing machine, comprising a printing wheel mounted to turn about a vertical axis, a platen coöperating therewith, 20 paper feed devices, an operating lever connected to the printing wheel and by means of which the latter is turned, connections between said lever and the platen for actuating the latter, a gage movable with the printing 25 wheel for determining the extent of movement of the paper feed devices, and means actuated by said operating lever for operating said paper feed devices variable amounts determined by the gage.

11. In a printing machine, the combination with a printing wheel and platen, of paper feed devices, a gage movable coincidently with the printing wheel and provided with a series of stops, a reciprocating 35 rod adapted to engage said stops, a block adapted to slide on said rod, a spring having its front end held against movement on the

rod and having its rear end in contact with the front of the block, an operating lever for turning the printing wheel and the stops 40 and for actuating the platen, means operated by said lever for moving said block and with it said rod toward the gage stops and connections between said rod and the paper feed devices. 45

12. In a printing machine the combination of a horizontally arranged printing wheel, a platen coöperating therewith, a series of horizontally arranged gage stops carried by and movable coincidently with 50 the printing wheel, paper feed devices, a horizontally arranged rod adapted to engage the stops, means for reciprocating said rod, a horizontally arranged slotted plate operatively connected with the rod, and connections between said plate and the paper feed devices. 55

13. In a printing machine, the combination of a printing wheel, gage stops, a reciprocating rod, a block mounted to slide thereon, a spring interposed between the block and the front portion of said rod, a slotted plate, a pin carried by the rod and operating in said slot, connections between said plate and the paper feed devices, an operating 60 lever for actuating the printing wheel and connections between said lever and said block whereby the latter is operated. 65

In testimony whereof, I have hereunto subscribed my name.

RAYMOND P. SLOAN.
